UNITED STATES PATENT OFFICE.

CHARLES W. SMITH, OF NORTH BALTIMORE, OHIO.

RAILROAD-TIE.

1,126,110.

Specification of Letters Patent. Patented Jan. 26, 1915.

Application filed February 27, 1914. Serial No. 821,503.

To all whom it may concern:

Be it known that I, CHARLES W. SMITH, a citizen of the United States, residing at North Baltimore, in the county of Wood 5 and State of Ohio, have invented a new and useful Railroad-Tie, of which the following is a specification.

The device forming the subject matter of this application is a metallic railroad tie, 10 and one object of the present invention is to provide a tie in which an adequate drainage may be secured.

Another object of the invention is to provide a railroad tie which, when the ballast 15 is properly tamped thereagainst, will not move endwise.

The invention aims to provide a railroad tie which will not readily tilt endwise or teeter under the action of the rolling stock.

It is within the scope of the invention to improve generally and to enhance the utility of, devices of that type to which the present invention appertains.

With the above and other objects in view 25 which will appear as the description proceeds, the invention resides in the combination and arrangement of parts and in the details of construction hereinafter described and claimed, it being understood that changes in the precise embodiment of the invention herein disclosed can be made within 30 the scope of what is claimed without departing from the spirit of the invention.

In the accompanying drawings:—Figure 5 1 shows in top plan, a tie constructed in accordance with the present invention; Fig. 2 is a section on the line 2—2 of Fig. 1, the rails being shown as added details; Fig. 3 is a section on the line 3—3 of Fig. 2; Fig. 4 is a section on the line 4—4 of Fig. 2; Fig. 5 is a perspective view showing one clip; Fig. 6 is a perspective view of one filler block; Fig. 7 is a fragmental section, similar to Fig. 2, but showing a modified form of the invention.

The tie herein disclosed preferably is fashioned from metal, saving as hereinafter modified, cast steel preferably being used.

The tie embodies a channel 1, the bottom of which is denoted by the numeral 2, the numeral 3 indicating the side walls of the channel. A portion of the bottom 2 of the channel, adjacent the center of the channel is struck upwardly as indicated at 4 to define a transverse recess 5 extended entirely through the tie, there being a depending web 6 extended longitudinally of the recess and

dividing the same into two opposed ballast receiving pockets 7.

The construction above described serves to 60 define a transverse partition in the intermediate portion of the tie, as will be understood best when Figs. 4 and 2 are compared.

At this point it may be noted that when the ballast is properly tamped into the pockets 7, an endwise movement of the tie will be prevented and, further, owing to the fact that the lower supporting base portions of the tie lie adjacent the ends of the channel 1, there will be but little tendency for the tie 70 to teeter vertically about a fulcrum lying intermediate the rails.

The side walls 3 of the channel 1 are connected adjacent the ends of the channel by platforms 8 spaced from the bottom 2, the 75 platforms preferably being formed integrally with the channel 1. Owing to the fact that the platforms 8 are formed integrally with the channel, the side walls 3 remain unencumbered, below the platforms 80 8; and thus water collecting within the contour of the channel 1 may flow readily out of the same. The inner ends 9 of the platforms 8 are spaced apart from the ends of the upstruck portion 4. By this construction, 85 water received in the intermediate portion of the tie may flow down and out beneath the platforms. At this point it may be noted that the upstruck portion 4 of the tie serves to prevent water from accumulating 90 adjacent the center of the tie. At their outer ends, the platforms 8 are equipped with abutments 10 preferably taking the form of upstanding flanges.

Resting upon the platforms 8 are filler 95 blocks 11 which may be made of wood. These filler blocks 11 are engaged at their outer ends by the abutments 10. In the filler blocks 11 are formed openings which may be variously positioned, the openings 100 preferably taking the form of longitudinal slots 12 which permit of a slight change of gage on sharp curves and elsewhere. Resting upon the filler blocks 11 and substantially co-extensive in length with the channel 1 is a top plate 14 having slots 15 which are alined with the slots 12 in the filler blocks 11.

Superposed upon the top plate 14 are clips 16, one of which is shown in detail in Fig. 5. 110 Each clip, denoted by the numeral 16 is provided with an opening 17. A securing element which may be a bolt and nut structure 18 passes through the opening 17 in the clip

16, through one of the openings 15 in the top plate 14 and through one of the openings 12 in the filler block 11, the platform 8 being provided with openings 28 which are adapted to receive the securing elements. By the construction above outlined, the clips 16, the top plate 14, the filler block 11 and the rail 24 are connected with the platform 8. Adjacent its inner end, the clip 16 is provided with a notch 19 and with an opposed notch 20, the notch 20 being slightly longer than the notch 19, measured longitudinally of the tie. It is in one or the other of these notches 19-20 that the flange of the rail 24 is received, as will be understood readily from Fig. 2. The clip 16 is reversible, and owing to the fact that the notches 19 and 20 vary in extent, rail bases of different widths may be accommodated as is necessary when a rail of a given weight is replaced by a rail of different weight. In order to prevent the clips 16 from shifting in the direction of the length of the tie, the clips are serrated transversely upon their upper and lower faces as shown at 21, the top plate 14 being serrated about the slots 15 therein, as indicated at 22. Obviously, when the serrated portions 22 and 21 are interengaged, the clip will not tend to move longitudinally of the tie. The clip 16 may be equipped upon its upper and lower faces with lugs 23 adapted to engage in the slots 15 of the top plate 14. These lugs, being engaged in the slots, tend to prevent the clip from swinging with the securing element 18 as a center. Obviously, by loosening the securing bolt 18, the clips may be shifted longitudinally of the rail, the slots 12 and 15 permitting this adjustment.

40 In Fig. 7 a modification is shown, wherein divers of the parts hereinbefore described are employed, these parts being designated by reference characters previously used, with the suffix "a". The modification shown in Fig. 7 consists in dispensing with the top plate 14 and using in lieu thereof an ordinary tie plate 25 upon which the rail 26 rests, spikes 27 being passed through the plate 25 into engagement with the filler blocks 11a. The block is held by bolts 18a.

50 Referring particularly to Fig. 2 of the drawings, in summing up the advantages of the invention, it will be observed that owing to the fact that the tie is provided intermediate its ends and in its bottom with the concavity indicated at 5, the tie will not tend to move endwise when the ballast is in place. Owing to the fact that this concavity or recess 5 is intersected by the depending web 6, the tie will not tend to move crosswise in the track. The transverse partition formed by the upstruck portion 4 of the bottom of the tie serves to prevent moisture from ac-

cumulating at the center of the tie. Since the platforms 8 are spaced from the bottom 65 2 of the tie, water may flow readily out of the ends of the tie, and this result is made possible by reason of the fact that the inner ends 9 of the tie are spaced apart from the ends of the transverse partition formed by 70 the upstruck portion 4 of the bottom of the tie. The clips 16 may be shifted longitudinally of the tie, toward and away from each other, and be held in adjusting positions by the securing elements 18. Further, the clips 75 16 may be inverted, to permit a change of the gage of the track. Since the clips and the top plate 14 are equipped with the serrations 21 and 22, the clips can not move endwise and, further, the clips can not swing 80 with the securing elements 18 as centers, because the lugs 23 upon the clips are engaged in the slots or openings 15 in the top plate 14.

Having thus described the invention, what is claimed is:-

1. A tie of the class described comprising a channel having an intermediate transverse partition and provided with platforms located adjacent the ends of the partition and spaced from the ends of the partition; fillers supported upon the platforms and rail holding means assembled with the fillers. 90

2. A tie of the class described, comprising a channel having an intermediate transverse partition and provided with platforms located adjacent the ends of the partition, the inner ends of the platforms being spaced from the partition, and the outer ends of the platforms having upstanding abutments; fillers resting on the platforms and 95 engaged by the abutments; and rail holding means assembled with the fillers. 100

3. A tie of the class described comprising a channel including a bottom and side walls, a portion of the bottom adjacent the center 105 of the channel being struck upwardly to define a transverse recess extended entirely through the tie, there being a depending web extending longitudinally of the recess and dividing the same into two opposed, 110 ballast-receiving pockets.

4. A tie of the class described comprising a channel having a platform extended there-across; a filler resting on the platform; a top plate resting on the filler; a clip resting 115 on the top plate; and a securing device engaged with the clip, the top plate, the filler and the platform.

In testimony that I claim the foregoing as my own, I have hereto affixed my signature 120 in the presence of two witnesses.

CHARLES W. SMITH.
